DESIGN FOR A SMOKING STAND

Edward Schultz, Chicago, Ill., assignor to The
Nagel-Chase Mfg. Co., Chicago, Ill., a corpora-
tion of Illinois

Application April 4, 1936, Serial No. 61,941

Term of patent 14 years

To all whom it may concern:

Be it known that I, Edward Schultz, a citizen of the United States, residing at Chicago, in the county of Cook and State of Illinois, have invented a new, original, and ornamental Design for a Smoking Stand, of which the following is a specification, reference being had to the accompanying drawing, forming a part thereof, wherein

The figure is a perspective view of a smoking stand showing my new design.

The design consists of a cylindrical body having circumferentially spaced ribs and bars which extend longitudinally between the upper and

lower ends thereof, the lower end or base comprising a circumferential band adjoining the cylindrical body and ribs and an enlarged circumferential base flange joined to said band by an intermediate band which is upwardly tapered from the base flange, and the upper end comprising an inwardly stepped circumferential band the outer step or rim of which adjoins the cylindrical body and ribs.

I claim:

The ornamental design for a smoking stand, as shown and described.

EDWARD SCHULTZ.
